UNITED STATES PATENT OFFICE.

HARRY F. BENSON, OF HOLYOKE, MASSACHUSETTS, ASSIGNOR TO WORTHINGTON PUMP AND MACHINERY CORPORATION, OF NEW YORK, N. Y., A CORPORATION OF VIRGINIA.

SHAFT BEARING.

Application filed January 28, 1921. Serial No. 440,605.

To all whom it may concern:

Be it known that I, HARRY F. BENSON, a citizen of the United States, residing at Holyoke, county of Hampden, and State of Massachusetts, have invented certain new and useful Improvements in Shaft Bearings, fully described and represented in the following specification and the accompanying drawings, forming a part of the same.

10 This invention relates to a driving head for vertical shafts such, for instance, as are used in connection with deep well pumps where, in addition to radial thrust, a large axial thrust is also present by reason of 15 the weight of the suspended parts and the column of water traveling through the pump.

One of the features of the present invention is the combination with a vertical shaft, 20 of radial and axial or end thrust bearings working in a reservoir sealed by lubricant, and wherein one of the rotating parts forms a pumping means delivering lubricant directly to the bearings.

25 A further object is to provide a driving head on which the bearings are so arranged that end thrust in either direction is amply taken care of by a proper bearing.

In the drawings:

30 Figure 1 is a vertical section through a well head showing the driving head in side elevation.

Figure 2 is a vertical section centrally through the driving head.

35 Figure 3 is a horizontal section on the line 3—3 of Figure 2.

Referring to the drawings:

The well head is mounted on the usual foundation plate 1 receiving the upper end 40 of the well casing 2 and mounting the frame 3 having the upper and lower bed plates 4 and 5, the lower bed plate 5 receiving the discharge tee 6 having the outlet 7 and the head 8 of said tee being provided with a 45 stuffing box 9 through which the vertical shaft 10 extends.

On the upper bed plate 4 is a member 11 having an opening 12 through which the shaft 10 projects. The member 11 receives 50 the base 13 of a load sustaining member A having the cylindrical side wall 14 closed at one end by the bottom 15 through the central boss 16 of which shaft 10 extends; a tube 17 is fitted in an oil-tight manner into 55 the bottom 15 and surrounds the shaft 10 so

that an annular lubricant reservoir is thus provided having outer and inner walls 14 and 17, respectively, clearance being allowed between the shaft 10 and the tube 17.

The upper end of the shaft 10 is threaded 60 as shown at 18, and below this threaded portion is a key 19 which is engaged by the keyway 20 of a sleeve 21, the upper end 22 of which is also threaded but with finer threads than the portion 18 of the shaft 10; 65 a hollow skirt 23, formed integral with the sleeve 21, telescopes over the tube 17 forming the inner wall of the lubricant reservoir and extends well down into the lubricant reservoir and, at its bottom, is provided with 70 a shoulder 24. Slipped onto the sleeve 21 and resting on shoulder 24 is a ball race 25 which cooperates with a race 26 on the cylindrical side wall 14, and with the balls 27 between the races forms the lower radial 75 bearing. Seating on the race 25 is a spacing sleeve 28 which fixes the position of an end thrust ring 29, said end thrust ring 29 cooperating with ball races 30 and 31 on each side thereof and with sets of balls 32 and 33 to 80 form axial or end thrust bearings; said races 30 and 31 having spherical surfaces resting on oppositely disposed spherical seats 34 and 35 of a thrust cage 36 carried on a shoulder 37 in the cylindrical wall 14. On 85 the upper side of the cage 36 is a ring 37 carrying ball race 38 cooperating with ball race 39 and balls 40 to form the upper radial bearing; the ball race 39 being spaced from the race ring 29 by a sleeve 41. A sleeve 42 is placed against the race 39 and over this is the cover plate 43 held by bolts 44 and which rests against the ring 37 to hold the ball race 38 and cage 36 in position.

Keyed to the upper end of the shaft 10, 90 as at 45 is the hub 46 of a pulley 47 extending down over the lubricant reservoir and forming an enclosure therefor, the inner side of the hub 45 resting on the upper end of the sleeve 42 to hold the bearing races 100 carried by the hollow sleeve 21 in position thereon, the pulley being held on the shaft 10 by a nut 48 screwed onto the upper end of the sleeve 21 and a lock washer 49.

Means for adjusting the shaft 10 axially 105 of the sleeve 21 is provided comprising a differential screw adjustment, preferably as shown, in which the upper end 22 of the sleeve 21 is suitably threaded to carry a nut 50 which is also in threaded engagement 110

- with the threaded portion 18 of the shaft 10. The threads on the upper end 22 of the sleeve 21 are finer than those on the shaft end 18 so that the cooperation of nut 50 with these relatively fine and coarse screw threads provides a differential screw adjustment for the shaft in which a slight vertical movement of the nut 50, either up or down, on the sleeve 21 produced by rotation of the nut 50 to the right or left secures a materially increased vertical movement of the shaft 18 to raise or lower the same for adjustment. A jamb nut 51 retains the nut 50 in adjusted position.
- 15 Radial passages 52 and 53 in the skirt 23 of the sleeve 21 cooperate with registering openings in the adjacent parts to form centrifugal pumping means, the passages 52 delivering oil to the thrust bearings from which it passes out at 54 at the top and bottom, and the passages 53 delivering oil to the upper radial bearing and out of ports 55 and down through vertical channels 56 to the lower radial bearing, thus maintaining a circulation of oil from within to without the sleeve 21 and flushing the bearings at all times with oil.
- 20 A pipe 57 leading from the bottom 15 of the annular lubricant chamber provides means for draining the same, while a pipe 58 leading from the bottom of one of the channels 56 and having vertical branches 59 and 60 mounts the filler cap B on one and the oil level indicating gauge C on the other.
- 25 It will be obvious that the side thrust of a belt driving the pulley 47 is absorbed by the upper and lower radial bearings, while end thrust on the shaft 10 is taken up by the two end thrust bearings, down thrust load being sustained by the thrust bearing cage 36 bearing on the shoulder 37 of the load sustaining member A while any upward thrust is taken care of against the cover plate 43.
- 30 I claim:
- 35 1. A vertical shaft bearing comprising a load sustaining member having outer and inner spaced walls forming a lubricant reservoir therebetween, a shaft surrounded by the inner wall exteriorly of the reservoir, a hollow sleeve carried by said shaft and telescoping over the inner wall and extending below the lubricant level to form a liquid seal, spaced radial thrust bearings between the outer wall of the lubricant reservoir and the outside of said sleeve, a laterally extending ring circumscribing said sleeve and confined against movement relative to the sleeve, bearing means carried by the load sustaining member and engaging the lateral faces of said ring, and lubricant pumping means in said sleeve for flushing the bearing means with lubricant.
- 40 2. A vertical shaft bearing comprising a load sustaining member having outer and inner spaced walls forming a lubricant reservoir therebetween, a shaft surrounded by the inner wall exteriorly of the reservoir, a hollow sleeve carried by said shaft and telescoping over the inner wall and extending below the lubricant level to form a liquid seal, spaced radial thrust bearings between the outer wall of the lubricant reservoir and the outside of said sleeve, a laterally extending ring circumscribing said sleeve and confined against movement relative to the sleeve, bearing means carried by the load sustaining member and engaging the lateral faces of said ring, and lubricant pumping means in said sleeve for flushing the bearing means with lubricant.
- 45 3. A vertical shaft bearing comprising a load sustaining member having outer and inner spaced walls forming a lubricant reservoir therebetween, a shaft surrounded by the inner wall exteriorly of the reservoir, a hollow sleeve carried by said shaft and telescoping over the inner wall and extending below the lubricant level to form a liquid seal, spaced radial thrust bearings between the outer wall of the lubricant reservoir and the outside of said sleeve, a laterally extending ring circumscribing said sleeve and confined against movement relative to the sleeve, bearing means carried by the load sustaining member and engaging the lateral faces of said ring, and lubricant pumping means in said sleeve for flushing the bearing means with lubricant.
- 50 4. In a shaft bearing, the combination with side and bottom walls 14, 15 and tube 17 forming an annular lubricant reservoir, of vertical shaft 10 within said tube carrying sleeve 21 outside said tube with oil space between the tube and sleeve, a bearing cage supported on the inner side of wall 14, opposing axial thrust bearings in said cage, radial thrust bearings between sleeve 21 and wall 14 above and below the thrust bearings, said sleeve 21 being provided with radial oil passages for pumping oil to the bearings from the oil space between sleeve 21 and tube 17, and oil delivery passages in sleeve 21.
- 55 5. In a shaft bearing, the combination with side and bottom walls 14, 15 and tube 17 forming an annular lubricant reservoir, of vertical shaft 10 within said tube carrying sleeve 21 outside said tube with oil space between the tube and sleeve, a bearing cage 36 supported on the inner side of wall 14 and carrying spherical ball seats 34, 35, ball races 30, 31 on said seats, thrust ring 29 and balls between said races, radial thrust ball bearings between sleeve 21 and wall 14 above and below the thrust bearings, said sleeve 21 being provided with radial oil passages for pumping oil to the bearings from the oil space between sleeve 21 and

tube 17, and oil delivery passages in sleeve 21.

6. The combination with shaft 10 carrying sleeve 21 with oil space between the shaft and sleeve, and radial oil passages through the sleeve, of outer wall 14 enclosing and separated from the sleeve, ball races and balls between the wall and sleeve forming

radial thrust bearings at top and bottom of the sleeve, and axial thrust ball bearings ¹⁰ between the wall and sleeve between the radial bearings.

In testimony whereof, I have hereunto set my hand.

HARRY F. BENSON.
